Design No. 18,289, dated May 1, 1888.

UNITED STATES PATENT OFFICE.

MINNIE B. KENT, OF NEW YORK, N. Y., ASSIGNOR TO THE BUTTERICK PUBLISHING COMPANY, (LIMITED,) OF SAME PLACE.

DESIGN FOR A LADY'S COSTUME.

SPECIFICATION forming part of Design No. 18,289, dated May 1, 1888.

Application filed April 2, 1888. Serial No. 269,380. Term of patent 3½ years.

To all whom it may concern:

Be it known that I, MINNIE B. KENT, of the city, county, and State of New York, have invented and produced a new and original Design for a Pattern of a Lady's Costume; and I do hereby declare that the engraved prints accompanying this specification convey to any one accustomed to using paper patterns a clear understanding of how a garment made up by the pattern will appear.

The design shows a basque and a round walking-skirt. The skirt displays a flat drapery that exhibits fan-plaits at either side; a full tablier falling straight to the edge in front of the plaits at the left side, and displaying draping-plaits at the belt, a deep looping at the right side, and a curved lower outline; a full back drapery falling deepest at the center and in jabot folds at the sides below draping.

plaits, and displaying plaits at the top and 20 loopings at either side of the center. The basque exhibits surplice fronts opening toward the shoulder over a pointed vest, and displaying fullness at the shoulders and short shirtings below the waist-line; a close-fitting position back that exhibits underfolded plaits 25 below the waist-line of its middle three seams; coat-sleeves, and a standing collar rolling over at the top.

What I claim as my invention, and desire to 30 secure by Letters Patent, is—

The design for a lady's costume, as shown in the engraved prints accompanying this specification.

MINNIE B. KENT.
